UNITED STATES PATENT OFFICE.

WILLIAM BROWNLOW ATKINSON AND JOHN HOWE FOSTER, OF FRANKLIN, KENTUCKY, ASSIGNORS TO THE AMERICAN COMBINATION DOOR LOCK COMPANY, OF SAME PLACE.

PERMUTATION-LOCK.

SPECIFICATION forming part of Letters Patent No. 291,665, dated January 8, 1884.

Application filed September 18, 1883. (Model.)

To all whom it may concern:

Be it known that we, WILLIAM B. ATKINSON and J. H. FOSTER, both of Franklin, in the county of Simpson and State of Kentucky, have invented a new and useful Improvement in Combination-Locks, of which the following is a full, clear, and exact description, reference being had to the annexed drawings, forming part of this specification.

10 This invention relates to combination or permutation door-locks; and it consists of an improvement on a part of the lock shown in Letters Patent No. 277,188, granted to the above-named Wm. B. Atkinson under date 15 of May 8, 1883. In the said patent is shown a combination-lock having ward-wheels in engagement with each side of a bolt having segmental and straight longitudinal slots, and an adjustable tumbler having clutches for setting 20 the ward-wheels either to hold or to release the bolt. The tumbler is made adjustable by means of a spindle formed in two parts, screwing one into the other, to provide for a longitudinal play in the casing of the sleeve supporting the tumbler and knobs.

25 Our present improvement consists of the means for adjusting the tumbler to throw it in and out of engagement with the ward-wheels, as hereinafter described and claimed.

30 In the drawings, Figure 1 is a side elevation of the lock, partly in section, and with the cap-plate and one of the ward-wheels removed; and Fig. 2 is a vertical cross-section of the lock through the knobs, showing part of a door.

35 A indicates the casing of the lock, provided with tubular projections B at its sides for supporting the ward-wheels C, C'. The ward-wheels are provided with lugs D, adapted to be turned through the segmental slots E in 40 the bolt F until arrested by the movable stops G in said slots or set in alignment with the straight longitudinal slots H, to allow the bolt to be moved.

Through a chamber, I, in the bolt is passed a sleeve, J, having a longitudinal slot, K, and in the sleeve is arranged a spindle, L, having a spiral groove, M, and a sleeve, N, arranged on the spindle and engaging with it by means of a lug, O, fitted in the said groove.

45 To the sleeve N is connected the tumbler P, which is adapted to move in the slot K as the sleeve N moves along the spindle L. The tumbler is provided with clutches or segmental gears Q at its sides, which are adapted to engage the clutches or gears of the ward-wheels when the tumbler is shifted from one to the other. The knobs R engage with the sleeve J by means of lugs S, fitting in the slot K, and the ends of the spindle L project through the knobs, and are provided with cross-pieces or 55 handles T, by which the spindle is to be rotated to shift the tumbler. The faces of the knobs are preferably made concave, and the handles T are countersunk therein.

60 The handles may be made in the form of wings, if desired, or in any other convenient or ornamental shape.

65 With the above construction no longitudinal play of the knob-spindle is required for shifting the tumbler, the rotation of the spindle being sufficient for that purpose.

70 The general operation of the lock will be understood from the above-named patent.

75 What we claim is—

The combination of the knobs, the slotted sleeve, the spindle having the spiral groove, the sleeve carrying the tumbler and having means for engaging with the said groove, and means for rotating the spindle to shift the tumbler, substantially as shown and described.

80 WILLIAM BROWNLOW ATKINSON.
JOHN HOWE FOSTER.
